UNITED STATES PATENT OFFICE.

EDISON E. RANDALL, OF KANKAKEE, ILLINOIS, ASSIGNOR TO PARAMOUNT KNITTING COMPANY, OF CHICAGO, ILLINOIS, A CORPORATION OF ILLINOIS.

MACHINE FOR SEWING LOOPED FABRICS.

1,205,107.

Specification of Letters Patent.

Patented Nov. 14, 1916.

Application filed November 19, 1915. Serial No. 62,406.

To all whom it may concern:

Be it known that I, EDISON E. RANDALL, a citizen of the United States, residing at Kankakee, county of Kankakee, State of Illinois, have invented an Improvement in Machines for Sewing Looped Fabrics, of which the following description, in connection with the accompanying drawing, is a specification, like characters on the drawing representing like parts.

This invention relates to a machine for uniting or sewing together the edges of knitted goods or looped fabrics, and as herein illustrated is particularly designed for sewing together the edges of such articles as stockings, as when the separately knit foot and leg portion are to be united, or as when the stocking is knit upon a circular knitting machine beginning at the toe, and the edges at the toe have to be united to complete the stocking. Machines of this general type and of various forms are well known in the art and usually comprise an intermittently rotating work supporting ring carrying a circular series of radially projecting impaling pins upon which the edges of the knit or looped fabric to be united are superposed and placed together with stitch forming mechanism which places a line of stitching immediately above the impaling pins in the projecting edges of the fabric. The articles thus to be stitched together are placed successively upon the impaling pins by the hand of the operative and owing to the exigencies of the work and the continuous operation of the machine the distance between the articles thus successively placed upon the impaling pins varies to a considerable degree. It is necessary, of course, to sever the stitching thread extending from one article to the next, and this has heretofore been done both by hand and by mechanisms provided for that purpose. But in neither case has the result been entirely satisfactory.

It is essential that the stitching thread projecting at each side of the sewed article shall be of a substantially uniform length varying only according to the character of the work. If this projecting thread is left too short it will ravel back and leave a hole. If it is left too long it is objectionable in appearance and uncomfortable to the wearer of the article. The United States Government recognizes the importance of the length

of the uniting thread by requiring in stockings furnished the Army that these ends shall not vary materially from $\frac{1}{4}$ ".

It is the object of the present invention to provide a simple and efficient automatic mechanism as a part of the machine which shall obviate all these difficulties, and shall insure the severance of the uniting thread to leave a uniform and predetermined length of projecting end.

The invention will appear more fully from the accompanying description and drawings and will be particularly pointed out in the appended claims.

The drawings represent so much of an ordinary form of machine for sewing looped fabrics as is necessary to an understanding of the present invention together with a preferred form of mechanism embodying the present invention.

Figure 1 is a top plan view of the machine; Fig. 2 is a radial side elevation partially in cross-section of the cutting mechanism and immediately adjacent parts; Fig. 3 is a view similar to Fig. 2 showing the cutting mechanism in a different period of its operation; Fig. 4 is a bottom plan view of the parts shown in Figs. 2 and 3 removed from the machine.

It is unnecessary to describe in detail a machine for sewing looped fabrics of the type herein illustrated because it is well known. The base 1 of the machine is usually secured to a suitable table or bench and carries the main shaft 2 from which the various mechanisms of the machine are operated and to which power is applied through a suitable pulley 3. An outwardly projecting overhanging arm 4 rises from the base 1 and carries depending therefrom at its outer end a stud 5 to which is rigidly secured the ring frame or support 6. The ring 7 is rotarily mounted upon the ring support and given an intermediate rotary movement by a pawl 8 operated from the main shaft 2 all in a well known manner.

The impaling pins 9 are of the usual form and are arranged on the ring 7 to project radially thereof. These pins are of sufficient length to hold the meshes of the edges of the given article such as a stocking which are to be united, and the operative places the articles successively upon these impaling pins leaving a more or less irregular portion projecting thereabove, and placing the ar-

6 ticles at various distances apart. A trimming mechanism comprising the horizontally movable trimming blades 10 operated from an eccentric 11 on the main shaft automatically trims off the upwardly projecting edges leaving only a sufficient portion projecting to be caught and united by the stitching mechanism.

10 In the construction illustrated the impaling pin rotates in the direction of the arrow in Fig. 1 and the article on the impaling pin after it passes through the trimmers 10 is brought into the field of action of the stitch forming mechanism which may be of any 15 suitable type, and is herein shown as comprising a needle arm 12 with its needle 13 operated from the main shaft of the machine, and suitable complementary mechanism. This stitch forming mechanism places 20 a line of stitching in the projecting edges of the articles upon the impaling pins immediately above the impaling pins. Frequently this mechanism operates with an over-edge stitch but in any event the portion 25 of the article projecting above the impaling pin when stitched together forms a welt or welt-like portion. The thread or threads carried by the stitch forming mechanism extend continuously from one article 30 to another just above the impaling pins.

35 The cutting mechanism of this invention, a preferred form of which as herein illustrated as located at any suitable point beyond the stitch forming mechanism, may be supported from any suitable portion of the machine and operated from any suitable moving part of the machine, and preferably is operated continuously.

40 A bracket 14 is herein shown as supporting the cutting mechanism and is shown as secured by screws directly to the ring support 6. This bracket extends radially outward. For convenience this outwardly projecting arm is made in two parts held together by the screws 15 and the part 16 has formed integrally therewith a transversely 45 extending hub or bearing 17.

50 The cutting mechanism comprises two relatively movable shearing blades the field 55 of action of which is located above the line of stitching in the stitched portion or the welt 18 formed thereby immediately above the impaling pins, and means are provided for raising or lifting the thread extending 60 from the stitched portion above the line of stitching or welt into the field of action of the cutting mechanism. In the preferred form of construction illustrated this result is secured by an inner shearing blade fixed 65 and extending down close to the impaling pins behind the welt while a second movable or pivoted co-operating shearing blade moves back and forth above the line of stitching or welt while an instrumentality therein termed 70 a thread lifter moves intermittently with the

movable sharing blade toward and from the fixed shearing blade. This lifter is long enough to contact with the projecting welt and is restrained in its movement thereby, but as the stitched article passes on the impaling pins this lifter being unrestrained by the welt passes beneath the thread and in its continued movement lifts the thread upwardly into the field of action of the shearing blades. At the same time a pusher is 75 preferably employed and is preferably movable with the movable shearing blades toward and from the base of the impaling pins to crowd up and maintain the stitched portion against the impaling ring. 80

85 The one shearing blade 19 which is preferably fixed or stationary in the form shown is mounted on the part 16 of the bracket arm so that it extends radially of the impaling pins, stands in a vertical plane, and with 90 its edge extending upwardly from a point behind the welt 18 immediately above the impaling pins. This blade may be adjustable to provide for wear and for that purpose is mounted on a pin 20 and held in place by a set screw 21. The movable shearing blade 22 is pivotally mounted by being secured to a shaft 23 mounted in the bearing hub 17. This shearing blade is at its cutting or effective edge shorter than the blade 19 and of such a length that as it swings back and forth it passes above the line of stitching or the welt 18 so that the field of action of the cutting mechanism is at all times above the welt 18. The movement of the movable shearing blade is secured by rocking the shaft 23. For this purpose a hub 24 is secured by the set screw 25 to the shaft 23 and is provided with an upwardly projecting arm 26 connected by a link 27 to some moving part of the machine, such for example as the pawl 8. 100

105 The thread lifter is herein shown as a finger 28 loosely pivoted on the shaft 23 and held in place by the set screw 29. This lifter is of such a length as in its movement to pass close above the impaling pin and contact with the welt 18. At its lower end it is curved inwardly to a point and lies close up against the pivoted shearing blade 110 22. It is yieldingly held toward the fixed shearing blade 19 by a spring 30 extending therefrom to a stud 31 on a fixed portion of the machine such as the part 16 of the bracket arm, and it is moved outwardly or 115 in the opposite direction by the movable shearing blade. For the latter purpose a portion of the lifter is bent laterally at 32 to engage the shearing blade 22. 120

125 The operation of this cutting mechanism will now be apparent. After the fabric on the impaling pins has been trimmed off by the trimmers and stitched by the stitching mechanism thus forming the slightly projecting stitched portion or welt 18 it passes 130

to the cutting mechanism. Preferably means are also provided for insuring and maintaining the position of the stitched fabric on the impaling pins up against the 5 periphery of the impaling ring. For this purpose a pusher is shown consisting of a metal blade or finger 33 secured to the hub 24 and bent downwardly extending tangentially and so positioned that as the hub and 10 shearing blade and pusher push inwardly the pusher will crowd the welt inwardly bringing the stitched work against the periphery of the impaling pin ring.

The operation of the mechanism will now 15 be apparent. As the work passes from the stitching mechanism it comes to the cutting mechanism and the stitched portion or welt 18 projects immediately in front of the lower edge of the fixed shearing blade 19. 20 The shaft 23 being in continuous intermittent vibration the movable shearing blade 22 and the lifter 28 swing toward and from the fixed shearing blade, the movable shearing blade passing above the welt 25 18 and the lifter striking against the welt and being restrained thereby against the action of the spring 30. This action continues until the stitched portion or welt 18 has passed out from the path of the lifter, 30 28 whereupon at the next inward swing of the lifter, there being no stitched portion or welt to restrain its movement, the lifter continues its movement passing under the projecting thread and past the fixed shearing blade 19 thus lifting the thread upwardly upon its inclined edge into the field 35 of action of the cutting mechanism, and as the edge of the movable cutting blade follows immediately after the projecting 40 point of the lifter the thread is at once severed. Owing to the repeated action of the mechanism if for any reason the thread should not be lifted and severed at the first vibration of the lifter after the welt 45 has passed, it will certainly be raised and severed upon a subsequent operation. The cutting mechanism continues to operate and sever any projecting end until the next article is reached when as the welt of the next 50 article passes into the path of the lifter the lifter is again restrained and the cutting operation prevented. Thus it will be seen that owing to the position of the lifter with respect to the cutting blades the projecting 55 ends of the thread are severed at substantially equal and uniform distances from the finished article because the point at which the thread shall be severed is determined by the stitched portion of the article itself.

60 Having fully described my invention, what I claim as new and desire to secure by Letters Patent is:

1. A machine for sewing looped fabrics comprising a movable impaling pin support, 65 impaling pins arranged thereon, stitch form-

ing mechanism for securing together the impaled looped fabrics by forming a line of stitching therein above the impaling pins, and continuously operated mechanism acting to raise the thread extending from the 70 stitched portion above the line where the stitching is formed and then to sever the said thread.

2. A machine for sewing looped fabrics comprising a movable impaling pin support, 75 impaling pins arranged thereon, stitch forming mechanism for securing together the impaled looped fabrics by forming a line of stitching therein above the impaling pins, continuously operated cutting mechanism 80 having its field of action located immediately above the line of stitching, and means to raise the thread extending from the stitched portion into the field of action of the cutting mechanism.

3. A machine for sewing looped fabrics comprising a movable impaling pin support, 85 impaling pins arranged thereon, stitch forming mechanism for securing together the impaled looped fabrics by forming a line of 90 stitching therein above the impaling pins, continuously operated cutting mechanism having its field of action located immediately above the line of stitching, and a continuously operated yielding thread lifter yielding upon engagement with the stitched portion but otherwise acting to raise the thread extending from the stitched portion into the field of action of the cutting mechanism.

4. A machine for sewing looped fabrics comprising a frame, an impaling pin support movably mounted thereon, impaling pins arranged on said support, stitch forming mechanism for securing together the impaled looped fabrics by forming a line 100 of stitching therein above the impaling pins, a fixed shearing blade mounted vertically on the frame and extending down to a point in the rear of the path of the stitched portion, a continuously operated co-operating 105 shearing blade movable above the path of said stitched portion, and an outwardly yielding lifter movable with said movable shearing blade extending down into the path of said stitched portion whereby it is 110 restrained from movement by contact with said stitched portion but otherwise acts to raise the thread extending from the stitched portion into the field of action of the shearing blades.

5. A machine for sewing looped fabrics comprising a movable impaling pin support, 115 impaling pins arranged thereon, stitch forming mechanism for securing together the impaled looped fabrics and forming a 120 welt therein above the impaling pins, a fixed shearing blade having its edge located in the rear of and extending above the said welt, a co-operating shearing blade mounted to move above the welt toward and from 125 130

and thus coöperate with said first shearing blade, and a thread lifter mounted to move toward and from the first shearing blade and, when not restrained by contact with the welt, to lift the thread above the welt into the field of action of the shearing blades.

6. A machine for sewing looped fabrics comprising a ring support, a ring rotarily mounted thereon, impaling pins arranged on said ring, stitch forming mechanism for securing together the impaled looped fabrics by forming a line of stitching therein above the impaling pins, a vertically and radially disposed fixed shearing blade mounted on the ring support with its edge in the rear of and extending above said stitched portion, a coöperating shearing blade pivotally mounted on the ring support and swinging above said stitched portion, means for continuously swinging said pivoted blade, and a pivotally mounted thread lifter yieldingly held toward the fixed blade and movable outwardly by the pivotal blade and extending into the path of the stitched portion whereby it is restrained from inward movement by contact with said stitched portion when opposite said stitched portion but otherwise acts to lift the thread above the stitched portion into the field of action of the shearing blades.

7. A machine for sewing looped fabrics comprising a ring support, a ring rotarily mounted thereon, impaling pins arranged on said ring, stitch forming mechanism for securing together the impaled looped fabrics by forming a line of stitching therein above the impaling pins, a vertically and radially disposed fixed shearing blade mounted on the ring support with its edge in the rear of and extending above said stitched portion, a coöperating shearing blade pivotally mounted on the ring support and swinging above said stitched portion, means for continuously swinging said pivoted blade, and means for causing the thread extending from the stitched portion when the stitched portion is out of line with said pivoted blades to be raised into the field of action of the said blades and thus severed thereby.

8. A machine for sewing looped fabrics comprising a ring support, a ring rotarily mounted thereon, impaling pins arranged on said ring, stitch forming mechanism acting to secure together the impaled looped fabrics by forming a stitched welt therein immediately above the impaling pins, a fixed shearing blade mounted on the ring support vertically and radially thereon, and extending down to a point in the rear of the path of the said welt, a continuously operated co-operating shearing blade movable above the path of said welt, and an outwardly yielding thread lifter movable with said movable shearing blade, extending down into the

path of said welt whereby it is restrained from movement by contact with said welt, but otherwise acts to raise the thread extending from the welt into the field of action of the shearing blades.

9. A machine for sewing looped fabrics comprising a movable impaling pin support, impaling pins arranged thereon, stitch forming mechanism for securing together the impaled looped fabrics by forming a line of stitching therein above the impaling pins, and mechanism including a part acting first to raise the thread extending from the stitched portion above the line where the stitching is formed and a part acting then to sever the said thread.

10. A machine for sewing looped fabrics comprising a movable impaling pin support, impaling pins arranged thereon, stitch forming mechanism for securing together the impaled looped fabrics by forming a line of stitching therein above the impaling pins, cutting mechanism having its field of action located immediately above the line of stitching, and means to raise the thread extending from the stitched portion into the field of action of the cutting mechanism.

11. A machine for sewing looped fabrics comprising a movable impaling pin support, impaling pins arranged thereon, stitch forming mechanism for securing together the impaled looped fabrics by forming a line of stitching therein above the impaling pins, cutting mechanism having its field of action located immediately above the line of stitching, and a yielding thread lifter yielding upon engagement with the stitched portion but otherwise acting to raise the thread extending from the stitched portion into the field of action of the cutting mechanism.

12. A machine for sewing looped fabrics comprising a movable impaling pin support, impaling pins arranged thereon, stitch forming mechanism for securing together the impaled looped fabrics by forming a line of stitching therein above the impaling pins, cutting mechanism having its field of action located immediately above the line of stitching, a yielding thread lifter yielding upon engagement with the stitched portion but otherwise acting to raise the thread extending from the stitched portion into the field of action of the cutting mechanism, a pusher, and means for intermittently moving it toward and from the base of the impaling pins to maintain the stitched portion against the impaling pin support.

13. A machine for sewing looped fabrics comprising a movable impaling pin support, impaling pins arranged thereon, stitch forming mechanism for securing together the impaled looped fabrics by forming a line of stitching therein above the impaling pins, continuously operated cutting mechanism having its field of action located immedi-

ately above the line of stitching, and a continuously operated yielding thread lifter yielding upon engagement with the stitched portion but otherwise acting to raise the 5 thread extending from the stitched portion into the field of action of the cutting mechanism, a pusher, and means for intermittently moving it toward and from the base of the impaling pins to maintain the stitched portion against the impaling pin support.

14. A machine for sewing looped fabrics comprising a movable impaling pin support, impaling pins arranged thereon, stitch forming mechanism for securing together the impaled looped fabrics and forming a welt therein above the impaling pins, a fixed

shearing blade having its edge located in the rear of and extending above the said welt, a coöperating shearing blade mounted to move above the welt toward and from and 20 thus coöperate with said first shearing blade, a thread lifter mounted to move toward and from the first shearing blade and, when not restrained by contact with the welt, to lift the thread above the welt into the field of 25 action of the shearing blades, and a pusher connected to and movable with said movable shearing blade to maintain the welt against the impaling pin support.

In testimony whereof, I have signed my 30 name to this specification.

EDISON E. RANDALL.
